UNITED STATES PATENT OFFICE.

CLARK L. SMITH, OF SPOKANE, WASHINGTON.

DESIGN FOR A CASKET.

50,880.

Specification for Design.

Patented June 5, 1917.

Application filed February 19, 1917. Serial No. 149,687. Term of patent 7 years.

To all whom it may concern:

Be it known that I, CLARK L. SMITH, a citizen of the United States, residing at Spokane, in the county of Spokane, State of Washington, have invented a new, original, and ornamental Design for a Casket, of which the following is a specification, reference being had to the accompanying drawing, forming a part thereof.

The figure is a perspective view of my casket illustrating my new design.

I claim:—

The ornamental design for a casket, substantially as shown.

CLARK L. SMITH.

Witnesses:

NATHAN ANDERSON,
P. M. STOCKWELL.
